UNITED STATES PATENT OFFICE.

GEORGE E. BARSTOW, OF LYNN, MASSACHUSETTS, ASSIGNOR TO THOMSON ELECTRIC WELDING COMPANY, OF LYNN, MASSACHUSETTS, A CORPORATION OF MASSACHUSETTS.

BREAKSWITCH.

1,190,621.

Specification of Letters Patent. Patented July 11, 1916.

Application filed October 16, 1909. Serial No. 523,062.

To all whom it may concern:

Be it known that I, GEORGE E. BARSTOW, a citizen of the United States, and a resident of Lynn, in the county of Essex and State of Massachusetts, have invented certain new and useful Improvements in Breakswitches, of which the following is a specification.

My invention relates to the construction of breakswitches such as used in electrical circuits to control the flow of current.

My invention more particularly relates to that class of switches in which a pivotally mounted contact is brought into engagement with a co-acting contact to complete the circuit, the main object being to bring the meeting surfaces of the two contacts into flat and square contact with each other simultaneously and so that when they are separated all parts of the meeting surfaces will break simultaneously whereby burning away of the corners of the contacts is avoided, which latter condition exists when one of the contacts is movable in an arc of a circle and the other is fixed or movable in any other path than the same arc as that traveled by the other contact.

Another object is to prevent the contacts wiping each other when breaking and also to decrease the flash usually attendant with the operation of this form of switch.

A still further object is to provide simple means for connecting the movable contacts into the electrical circuit direct without having to secure the circuit wires to movable parts or being compelled to conduct the current across sliding connections.

To these ends my invention consists broadly in a pair of pivotally mounted contacts both adapted to turn about a common center when making and breaking circuit whereby the meeting surfaces of the contacts will engage each other or be disengaged from each other simultaneously over all parts of the meeting faces.

My invention consists further in the novel parts, combinations of parts and details of construction hereinafter more particularly described and then specified in the claims.

In the accompanying drawings, Figure 1 is a side elevation of a breakswitch constructed in accordance with my invention, the protecting cover being shown in section. Fig. 2 is a plan view of the same, the cover being cut by a horizontal section. Fig. 3

is a front elevation of the breakswitch. Fig. 4 is a side elevation of the breakswitch, parts being broken away, and illustrates the position of the parts when the circuit has been broken, the figure being shown on a reduced scale from the previous figures. Fig. 5 is a longitudinal vertical section, on a reduced scale, taken on the line A—A Fig. 2. Fig. 6 is a similar section, on a reduced scale, taken on the line B—B Fig. 2. Fig. 7 is a transverse vertical section, on a reduced scale, taken on the line C—C Fig. 2, and looking in the direction indicated by the arrow D.

In the drawings, 1 indicates the base and 2 indicates the protecting cover within which the various parts of the breakswitch are located, while 3 indicates a supplemental slate base upon which the various parts of the switch proper are mounted and which is mounted on the main base 1 in any suitable manner.

4 and 5 indicate a pair of preferably parallel contact arms or levers loosely fulcrumed on a common pivot 6 secured to a bracket 7 rising from and secured to the base 3.

The contact arm 4 is provided with a contact 8 secured to and projecting from the free end of the arm, the said contact being preferably in the form of a plate or strip of copper and suitably insulated from the arm. The contact arm 5 is provided at its free end with an offset 5' upon which the lower contact 9 is mounted to bring it directly under the upper contact member 8, whereby when the contact arms 4 and 5 are brought together, the upper surface of the contact 9 and the lower surface of the contact 8 will simultaneously engage over their entire meeting surfaces, the said lower contact 9 being also suitably insulated from the contact arm 5.

A spring 10 compressed between the contact arm 5 and a fixed support tends to always force the contact 9 upward and toward the contact 8, the upward movement of the contact 9 being limited by a stop 11 secured to the contact arm 5 engaging a wall of the bracket 7.

The contact arm 4 carrying the upper contact is preferably normally held in raised or open position by a pair of springs 12, 13 acting on a rearwardly extending arm 4' of the lever 4 through a lever 14 fulcrumed on

a suitable boss 15 secured to the base 1. The spring 12 connects the arm 4' with an end of the lever at one side of the fulcrum and the spring 13 connects the end of the lever 5 at the other side of the fulcrum with a fixed support such as a pin 16 projecting from the bracket 7. By this construction a quick break between the contacts 8 and 9 is obtained, the upward movement of the contact 10 lever 4 and contact 8 being limited by a stop 17 secured to the lever 4 engaging a wall of the bracket 7.

The contacts 8 and 9 might be brought together by any desired means, this being accomplished in the present case by a chain 18 secured to a pin 19 on the contact arm 4 which passes downward through openings in the bases 1 and 3 and over a sheave 20 mounted below the base 1 after which the 20 chain is passed to any desired point, to be operated by hand or otherwise. In the present case the contacts would be brought together by a pull on the chain 18 and held down thereby and when desired to break the 25 circuit, the chain is released and the springs 12, 13 force the contacts apart.

21, 22 indicate fixed terminal posts or brackets mounted on the supplementary base 3 and to each of which the ends of the circuit 30 wires are secured. The circuit is carried from the terminal post 21 to the lower contact 9 by a flexible lead 23 composed of laminated copper strips secured at one end to the post 21 and at the other end to the 35 contact 9, whereby movement of the contact is permitted. Similarly the circuit is carried from the terminal post 22 to the upper contact 8 by a lead of superimposed laminated copper strips 24 secured to the post 22 and to 40 a bracket 25 secured and carried by the contact 8.

By this construction when the contacts are brought together they will simultaneously engage all parts of the meeting surfaces of the two contacts and when the springs 12, 13 force the upper contact away, the spring 10 forces the contact 9 to follow for a short distance, but in this movement the contact 9 travels in the same arc as the 50 contact 8, so that when the final rupture takes place all the parts of the meeting surface of the contact 8 will leave the surface of the contact 9 at the same time.

It will be understood that my invention 55 is not limited to the particular form and construction shown and described but is capable of being carried out in various modifications and arrangements without departing from the spirit thereof as defined in the 60 appended claims.

What I claim as my invention is:

1. In a breakswitch, the combination of two coöperating contact arms, a common pivotal support for said arms, rigid flat-surfaced contacts adapted to engage each other and carried by the ends of said arms but insulated therefrom, flexible conductors secured to said contacts, means normally separating said contacts, means tending to cause one contact arm to follow the movement of the other and press the contacts together and means limiting the movement of the last-named arm.

2. In a breakswitch, the combination of a pair of contact arms, a common pivotal support for said arms, coöperating rigid flat contacts carried by the end of each arm and insulated therefrom, the arcing surfaces of said contacts being at right angles to the direction of their movement, flexible electric connections to said contacts, means normally separating said contacts, means tending to cause one contact arm to follow the movement of the other and press the contacts together and means limiting the movement of the last-named arm.

3. In a breakswitch, the combination of a pair of contact arms, a common pivot on which said arms are mounted, a contact secured to but insulated from the end of one 90 of said arms, a coöperating contact secured to but insulated from the end of the other arm and offset therefrom to bring it in line for engagement with the first-named contact, a flexible electric connection secured to 95 each of said contacts, means normally separating said contacts, means tending to cause one contact arm to follow the movement of the other and press the contacts together and means limiting the movement of the last-named arm.

4. In a breakswitch, the combination of a pair of freely mounted contact arms, a common pivot on which said arms are mounted, a contact carried by but insulated from the 105 end of each arm, said contacts being adapted to engage each other, flexible conductors secured to said contacts, a stop for one of said arms and a spring acting on said arm and adapted to follow up and press the contact of said arm against the coöperating contact.

Signed at Lynn, in the county of Essex and State of Massachusetts, this 14th day of Oct., A. D. 1909.

GEORGE E. BARSTOW.
